UNITED STATES PATENT OFFICE.

HJALMAR NORDVALL AND MANUEL PETERSON, OF DALTON, MICHIGAN.

FASTENING DEVICE.

1,169,859.

Specification of Letters Patent.

Patented Feb. 1, 1916.

Application filed April 25, 1914. Serial No. 834,534.

To all whom it may concern:

Be it known that we, HJALMAR NORDVALL, a subject of the King of Sweden, and MANUEL PETERSON, a citizen of the United States, 5 residing at Dalton, in the county of Muskegon and State of Michigan, have invented a new and useful Fastening Device, of which the following is a specification.

Our invention relates to a fastening device to be known as adjustable sack ties, which said fastening device consists of a small twisted, pliable steel hook which may be tied to the end of a string or a band through an eye in the hook; and the objects 10 of said improvement are, first, to produce a method of tying bags, fastening horse blankets, and tying or fastening similar other articles in a speedy and secure manner and second, to afford a method in which 15 said sacks, horse blankets or similar other articles may be untied equally as fast and in as easy a manner. We attain these objects by the small twisted, pliable steel hook illustrated in the accompanying drawings, in 20 which—

Figure 1 is a full view of entire device with band or string fastened in loop marked 3. Fig. 2 is a plan view of twisted steel hook not attached to string or band.

30 In Fig. 1, numeral 3 refers to eye of hook in which string, numeral 4, is tied; numeral

5 refers to the string or band as fastened in the loop caused by a bending of said steel hook while numeral 6 refers to spring of 35 said steel hook which is so adjusted to prevent band or string from slipping back and coming loose; numeral 7 refers to the end of the string or band which is to be pulled toward the eye, numeral 3, to untie band or string instantly.

40 Having thus fully described our invention, what we claim as new and desire to secure by Letters Patent of the United States is—

In a bag fastener, a cord and a resilient 45 wire cord holder consisting of a body bent into the form of a thin V, one arm terminating in an eye for receiving the other end of said cord, the other arm bent back so that the end partly closes the opening of the V, 50 but permits a cord to be forced past the retaining end and into engagement with the V notch.

55 In testimony whereof we have signed our names to this specification in the presence of two subscribing witnesses.

HJALMAR NORDVALL.
MANUEL PETERSON.
